REFRIGERATING APPARATUS

Martin J. Goulooze, Grand Rapids, Mich., assignor to Nash-Kelvinator Corporation, Detroit, Mich., a corporation of Maryland

Application November 9, 1940, Serial No. 365,135

4 Claims. (Cl. 220—9)

The present invention pertains to refrigerators, and more particularly to refrigerator cabinet construction.

It is an object of the present invention to construct a refrigerator cabinet having inner and outer walls interconnected by a non-heat conducting breaker strip and to provide a protecting cover for said breaker strip.

It is another object of the present invention to interconnect the inner and outer walls of the cabinet peripherally adjacent to the opening to the food storage compartment so as to form the front wall of the cabinet.

It is still another object of the present invention to provide metallic cover members over the breaker strips formed of relatively thin gauge material, and having a relatively low heat conduction value so as to minimize the transfer of heat from one wall to another.

It is still another object of the present invention to form the cover member from an alloy such as stainless steel or the like and to provide a series of corrugations therein to reinforce it against buckling and the like.

A still further object of the present invention is to affix the cover members in position without the use of extraneous affixing means.

A still further object is to arrange the cover members as to be relatively adjustable to permit a close abutting fit therebetween.

The invention itself, however, both as to its organization and its method of operation, together with additional objects and advantages thereof, will best be understood from the following descriptions of specific embodiments when read in conjunction with the accompanying drawings, in which:

Fig. 1 is a front elevational view of a refrigerator cabinet with parts broken away showing the invention embodied therein;

Fig. 2 is a fragmentary cross-sectional view taken along line 2—2 of Fig. 1;

Fig. 3 is a fragmentary front elevational view of a corner of the cabinet with parts broken away and parts shown in section;

Fig. 4 is a fragmentary rear view of the corner of the cabinet with the inner and outer wall in section;

Fig. 5 is a fragmentary cross-sectional view taken along line 5—5 of Fig. 4;

Fig. 6 is a fragmentary cross-sectional view taken along line 6—6 of Fig. 3;

Fig. 7 is a front elevational view of a cabinet with parts broken away and parts shown in sec-

tion embodying a modified form of the invention;

Fig. 8 is an enlarged fragmentary cross-sectional view taken along line 8—8 of Fig. 7;

Fig. 9 is an enlarged fragmentary cross-sectional view taken along line 9—9 of Fig. 7;

Fig. 10 is an enlarged fragmentary cross-sectional view taken along line 10—10 of Fig. 7;

Fig. 11 is an enlarged fragmentary cross-sectional view taken along line 11—11 of Fig. 7; and

Fig. 12 is an enlarged fragmentary cross-sectional view illustrating method of assembly.

Shown in the drawings is a refrigerator cabinet 20 having a food storage compartment 22. A swingably mounted door 24 closes the opening 25 to the compartment. The cabinet is formed with an outer shell 26 enclosing in spaced relation an inner liner 27 which forms the walls of the food storage compartment. Heat insulation material 29 is placed between the liner 27 and shell 26.

The shell 26 is bent at right angles to form a marginal trim edge 30 extending in spaced relation about the opening 25. The edge 30 is formed S-shaped in cross-section with a folded back portion 32 extending back to the corner edge and thence rearwardly with the side panel a short distance, thence bent at right angles to extend forwardly in spaced parallel relation to the trim edge 30 forming a supporting flange 34. The flange 34 is greater in width than the trim edge 30 so as to threadably receive metal screws which clear the edge of trim 30. The flange 34 spaced from the trim 30 forms a pocket or groove 36 therebetween.

The liner 27 is formed with a marginal flange 37 that extends peripherally about the opening 25 towards and in planular alignment with the flange 37. The flanges 37 and 34 terminate a spatial distance apart, and are joined together by a non-heat conducting breaker strip 40. A longitudinal edge of the breaker strip 40 is received in pocket 36 and is secured by screws 42 to flange 34. The opposite edge of the breaker strip lies against the face of flange 37 and is secured thereto by screws 44 threadably receivable by the speed nuts 45 that are securely clipped to rearwardly extending edge 46 of flange 37.

The speed nuts 45 are set and clipped to flange 37 at spatial intervals to receive screws 44 for fastening the breaker strip to the liner. The breaker strip may be directly secured by threading the screws into the flange 37, but where the liner and flange are coated with vitreous enamel 50 speed nuts are desirable as the enamel readily

chips when screws and the like are attempted to be threaded therethrough.

To provide a protective covering for the breaker strip and conceal the heads of the screws a thin metallic sheet having a thickness of approximately .003 to .010 of an inch is preferably used to form a trim cover 50 to extend over the breaker strip 40. The cover 50 is preferably formed of stainless steel though it may be formed of other material and suitably coated with enamel, or it may be plated. The cover extends over the face of the breaker strip with a longitudinal edge extending into the groove 36 adjacent the rear side of trim 30. The cover is held in close abutment against the trim by the flange 34 which tends to press in a forwardly direction constricting the width of the groove to the thickness of breaker strip and cover. The opposite longitudinal edge of cover 50 is marginally bent to extend rearwardly at right angles, an at an intermediate longitudinal line is bent to extend inwardly at an inclined angle to form a locking flap 54. The flap 54 frictionally engages the inclined side 55 of recess 56 extending longitudinally along the edge of the breaker strip lying adjacent the face of flange 37. The inclined side 55 extends to form a restricted opening with the flange 37 into the recess 56. As the flap 54 frictionally engages the side 55 the corner edge 52 of the flap will abut against the face of flange 37 held thereagainst by the tension of the flap 54 against side 55 and the tapering corner edge of the breaker strip. The frictional engagement of flap 54 against the inwardly inclined side 55 binds the cover to the breaker strip against accidental withdrawal therefrom.

The door 24 is constructed with an outer panel 60 and an inner panel 62 spaced therefrom to provide therebetween heat insulation material 64. The outer panel 60 is secured by weld to member 65. Screws 67 secure the inner panel 62 to member 65 and also a peripherally extending balloon type door seal 70 by means of a tongue section 71 that is interposed between the frame and the inner panel. The tongue is formed integral with the gasket 70 and also serves to insulate the panel 62 from the member 65 against heat conduction. The seal 70 is formed to overlie and conceal the screwheads, and is adapted to seal against the trim edge 30 of the outer shell when the door is in closed position.

In the present construction, the breaker strips are secured in sections across the top, bottom and the vertical sides adjacent to the rectangular opening 25. Each of the breaker strips is provided with a respective cover 50 so that there is left a small gap between the sections in each of the four corners. To conceal and cover these gaps there are provided T-shaped corner strips 72. Each corner strip 72 is formed with a face portion 74 which overlies and bridges the adjoining cover sections, and a U-shaped portion 75 that extends longitudinally along the rear side of face portion 74 adapted to engage under and around an end of the cover and breaker strip (see Fig. 6). One end of the corner strip enters into groove 36, and its opposite end is turned to extend towards the face of flange 37 to form a corner 76 between the abutting cover sections. In attaching the member 72 to the structure it is slid horizontally between the gap so that the U-shaped section engages around an end of a cover and breaker strip and the end of member 72 inserted between the cover 50 and trim edge where it is frictionally locked against withdrawal.

Thus the corner strip 72 serves to lock the cover to the breaker strip while at the same time it is securely held in position.

The interconnecting breaker strips securely support the liner 27 to the shell 26. To further support the liner 27 to the shell against inward and outward movement, as may occur by the slamming of the refrigerator door, there are provided corner supports or gussets 90. Plates 91 are welded to each corner on the inner side of flange 37 which is in alignment with gussets 90 which extend diagonally across the corners within the outer shell and welded to the rear side of flange 34. In assembly, as the liner is set within the shell the plates 91 are secured by metal screws 94 to a respective gusset 90 after being spaced therefrom by non-heat conducting spacers 95.

In Figs. 7 to 12 there is shown a modified form of the invention embodied in a refrigerator cabinet 100. The cabinet 100 comprises outer shell 102 and inner liner 104. The outer shell 102 is similarly formed and constructed to the shell 26 described in the preferred form having an inwardly turned trim edge 105 which is formed S-shaped in cross section with a spaced parallel flange 106 and the groove 107 therebetween. The inner liner 104 is flanged outwardly, as at 109, to extend towards flange 106. Secured by weld, solder or the like to rear side of flange 109 is a securing strip 110 periodically perforated to threadably receive metal screws 111 in the securing of breaker strip 112. The flange 109 is bored to permit free passage of the metal screws therethrough to prevent chipping the coating of vitreous enamel thereon. The opposite end of breaker strip 112 is secured to flange 106 by screws 114.

Longitudinally extending recesses 116 and 117 are formed in the breaker strip 112. The recess 116 is formed on the face of the breaker strip along the edge that lies behind the trim edge 105. The recess 117 is formed on the rear side of the opposite side edge of the breaker strip 112 adjacent to the face of the flange 109.

Adapted to lie over the face of the breaker strip is a thin metallic cover member 120 preferably not exceeding in thickness .010 of an inch. The cover member 120 is secured by having a longitudinal edge folded, as at 122, and inserted behind the trim portion 105. The folded edge section 122 engages in the recess 116 becoming locked therein by a slight spreading of the folded portion with the end of section 122 abutting the edge of the recess when attempted to be withdrawn. The opposite longitudinal edge of the cover member is marginally bent to engage around and cover the exposed end of the breaker strip and the end section 124 entering the recess 117. The end 124 is bent to extend diagonally across in the recess 117, and tensioned so as to hold the edge 127 in abutment against the face of flange 109 along its entire longitudinal length.

A door 130 swingably supported on hinges 132 is provided for closing the opening to the storage compartment. The door is similar in construction to the door 24 described in the preferred form.

As will be noted in Fig. 7, the breaker strips are secured, about the rectangular opening, in sections which comprise vertical pilaster sections 140 joined by the horizontally extending top and bottom sections 141. Each of the breaker strip sections are provided with a respective cover member 120. The cover members on the hori-

zontal sections 141 are laterally adjustable relative to its respective breaker strip so as to be movable into close abutting relationship with the vertical pilaster sections 140. The inturned flanges 122 of the cover members are sufficiently spaced from the abutting edge of its respective recess 116 to permit a movable adjustment of the cover member towards its adjacent cover member. The cover members 120 on the pilaster section are provided with inturned ends 145 (see Fig. 11) against which the horizontal cover members abut. Sufficient frictional tension is provided by the folded section 122 and the end 124 against the breaker strip to maintain the cover member in its relative adjusted position. By permitting vertical movement of the top and bottom horizontally extending cover members, a close abutting fit may be at all times arranged without the need or use of corner cover straps to close any gaps therebetween.

In the modified forms the cover members are shown corrugated with the corrugations extending longitudinally thereof. This is necessitated in some cases due to the thinness of the metal to add rigidity for greater ease in handling during the manufacturing process and assembling to the cabinet. It will appear obvious that other designs may be impressed or rolled in the structure to lend both attractiveness and rigidity, or it may be left plain as shown in the preferred form. If desired corrugated strips may be used in the cabinet shown in Fig. 1.

Thus it will be noted that there is an arrangement for the interconnecting and supporting of the liner to the shell by insulation strips extending peripherally about the opening to the food compartment and forming the front wall of the cabinet. The insulation strips are concealed by a decorative cover arranged to embrace the insulation strip without the use of extraneous affixing means. Further, the arrangement is such that the covers are held in a close fit against the edge of the outer shell and flange of the liner.

While I have described the preferred form of my invention, I do not wish to limit myself to the precise details as shown, but wish to avail myself of such variations and modifications as may come within the scope of the appended claims.

I claim:

1. A cabinet construction comprising inner and outer spaced apart shells, the outer shell having a pocket and a flange extending toward the inner shell, the inner shell having a flange extending toward the outer shell with both of said flanges being positioned on substantially the same plane, a breaker strip extending across said flanges with one edge thereof being positioned in said pocket, means securing one side of said breaker strip against said flanges and a relatively thin covering member extending across the outer face of

said breaker strip with one edge thereof extending into said pocket and the other edge thereof being wrapped around one edge of said breaker strip and releasably secured between said breaker strip and one of said flanges.

5 2. A cabinet construction comprising inner and outer spaced apart shells, the outer shell having a pocket and a flange extending toward the inner shell, the inner shell having a flange extending toward the outer shell with both of said flanges being positioned on substantially the same plane, a breaker strip extending across said flanges with one edge thereof being positioned in said pocket, means securing one side of said breaker strip against said flanges and a relatively thin covering member extending across the outer face of said breaker strip with one edge thereof extending into said pocket and the other edge thereof being wrapped around one edge of said breaker strip and releasably secured in a notch formed in said breaker strip between said breaker strip and one of said flanges.

10 3. A cabinet construction comprising inner and outer spaced apart shells, the outer shell having a pocket and a flange extending toward the inner shell, the inner shell having a flange extending toward the outer shell with both of said flanges being positioned on substantially the same plane, a breaker strip extending across said flanges with one edge thereof being positioned in said pocket, means securing one side of said breaker strip against said flanges and a relatively thin corrugated covering member extending across the outer face of said breaker strip with one edge thereof extending into said pocket and the other edge thereof being wrapped around one edge of said breaker strip and releasably secured in a notch formed in said breaker strip between said breaker strip and one of said flanges.

15 4. A cabinet construction comprising inner and outer spaced apart shells, the outer shell having a pocket and a flange extending toward the inner shell, the inner shell having a flange extending toward the outer shell and a rearwardly directed portion extending from the inner shell flange with both of said flanges being positioned on substantially the same plane, a breaker strip extending across said flanges with one edge thereof being positioned in said pocket, means engaging said rearwardly directed portion for securing one side of said breaker strip against said flanges and a relatively thin corrugated covering member extending across the outer face of said breaker strip with one edge thereof being positioned in said pocket between the breaker strip and one wall of said pocket and the other edge thereof being wrapped around one edge of said breaker strip and releasably secured in a notch formed in said breaker strip between said breaker strip and one of said flanges.

20 50 MARTIN J. GOULOZE.
